UNITED STATES PATENT OFFICE.

LUTHER SADLER, OF LOS ANGELES, CALIFORNIA, ASSIGNOR OF ONE-THIRD TO E. L. FAIRBANKS AND ONE-THIRD TO L. C. TREADWAY, BOTH OF LOS ANGELES, CALIFORNIA.

RAILWAY-TRACK CROSSING.

Application filed June 4, 1928. Serial No. 282,600.

This invention relates to track crossings for railroads generally but particularly for street railways, and the objects of the invention are to provide improvements in a track crossing construction which will overcome the pounding of the car track wheels on the gaps provided in the crossing rails to permit the wheel flanges to roll through. Also such a construction which may quickly be converted to the common crossing if for any reason it should be desired.

Briefly described my improvements comprise providing a plurality of special turntables or plugs in the intersecting rails all 15 geared or linked together so that they may be revolved to bridge the crossing gaps in the treads of the rails, optionally in either direction of travel, the turntables to be endwise reversible to convert the crossing into a common gap crossing. Other features are the particular form and position of the plugs, their offset relation to the rail flange, the proximity of the operating levers to the rails whereby accessibility for inspection and 20 pairs is obtained. Other features of advantage will appear in the drawings and following description.

In the drawings Fig. 1 is a plan view of my improved rail crossing taken at grade. 30 Fig. 2 is a plan view of the complete structure showing the special arrangement of foundation or ties beneath the crossing. Fig. 3 is a cross section of Fig. 2 taken along the line 3—3 thereof.

Fig. 4 is an end view of Fig. 2.

Fig. 5 is a sectional plan view taken through the revolvable turntables or plugs. Fig. 6 is a cross section of the complete installation as seen from the line 6—6 of Fig. 40 5. Fig. 7 is a cross section of the installation as seen from the line 7—7 of Fig. 5.

Fig. 8 is an enlarged plan view of the intersection of two rails showing the plug and its operating arm.

Fig. 9 is a central sectional elevation of Fig. 8.

Fig. 10 is a lower end view of the plug only of Fig. 9 as seen from the line 10—10 thereof.

The invention may be applied to a crossing embracing any number of rails and of any type of rails, but is here shown applied to a pair of common flange rails crossing another pair at right angles. The rails are

designated 1 and at the intersection is a crossing rail unit designated 2.

This crossing unit is grooved at 3 to continue the flanges of the rails and provided with rail head or tread portions 4 continuing the rail treads.

At the center of each point of crossing of the treads is a turntable or plug 5 revolvably positioned in an enlargement or housing 6 formed integral with the crossing unit and it should be observed that the plugs are centered substantially on the crossing center 65 lines of the rail head and of a diameter reaching just beyond the flange groove 3 of the crossing.

One side of the upper end of each plug is stepped away as at 7 to align with and form 70 a continuation of the flange groove 3 and will align with either groove upon revolving the plug ninety degrees.

The lower end of each plug rests upon a loose steel sole disk 8 (see Fig. 9) and under 75 the disk is an annular recess 9 formed in the lower portion 6' of the housing which forms a reservoir adapted to hold a quantity of lubricant.

The plug as described may be freely lifted 80 from the vertical bore of the housing and reversed therein, and when so reversed will form a common gap crossing as its lower end is stepped away at two sides at 10—10 at right angles so as to continue the flange 85 grooves 3 of the rails in both directions.

The inner wall of the housing is open as indicated in Fig. 9 to provide means for revolving the plug, and which means comprises an eyebolt or arm 11 screwed into the side of 90 the plug. This arm passes just below a shoulder 12 on the housing and thus prevents the plug from being pulled upward until the arm is removed. Also the arcuate movement of the arm in revolving the plug may be 95 limited by the opening in the housing in which it operates so that when fully over either way one or the other of the rails will have its flange groove opened up for travel and the opposite grooves closed.

The four plugs of one crossing are (as shown in Fig. 5) all swung inwardly or outwardly from or toward the common center of the crossing, to align the opposite runs of rails, through the medium of a rock shaft 13 105 passing transversely through two of the cross-

ing rails and rotatably supported in bearings 14 secured to their webs.

To this rock shaft adjacent the inner webs of both rails is secured a pair of rocker arms 5 or double ended cranks 15, to the opposite ends of which are pivotally connected reversely extending rods or links 16-17 in turn pivoted at their outer ends at 18-19 to the eyebolts 11 which project from the turn-
10 tables or plugs 5.

Link 17 is of goose-neck form, while link 16 is substantially straight, and both links are connected to the rocker arm 15 by universal joints 35 to care for the horizontal and vertical arcs of travel involved.
15

Pivottally connected with one of the rocker arms and extending horizontally along the inner side of the web of the rail is an operating link 20 pivotally connected at its outer 20 end to a crank 21 secured to a short hollow shaft 22 extending transversely through the rail web in a bearing 23 secured thereto and at the outer end of the shaft is a crank 24 which may be operated by any desired means, 25 such for instance as the pull and push rod 25 which may extend to a tower house or any convenient type of ground lever or other operating device not shown.

The operating levers and all bearings it will 30 be noted, lie along two rails only, and this provides for reaching all working parts through removable surface plates 26, 27, 28, 29, 30, supported on recessed edges 31 on the main crossing members and auxiliary members 32 as best shown in Fig. 3.

The foundation structure of my crossing is unique inasmuch as two of the crossing rail members are of a depth to rest on a layer of ties 33, and the two oppositely extending 40 members are of an increased depth to rest on a second layer of ties 34 extending transversely under the upper layer, and it is along the deeper sectioned rails that the operating mechanism extends and from which it is operatively supported.
45

I am aware that other rail crossing structures embodying revolvable plugs have been previously constructed, notably the structure shown in my joint Patent No. 1,169,196 but 50 they do not embody the improvements above described and hereinafter claimed.

I claim:

1. A unitary structure of crossed railway rails, a vertically depending cylindrical housing at each rail intersection, and a circular plug revolvably positioned in said housing with its upper end flush with the rail tread, a step formed across the upper end of the plug adapted to continue the wheel flange 55 groove of either rail when the plug is turned, said plug being endwise reversible in the housing and the opposite end of the plug 60 formed to continue the wheel flange grooves of both crossing rails when the plug is held in fixed position with said opposite end up.
65

2. In a track crossing structure a reversible revolvable track plug provided at one end with a formation adapted to match and continue the rail surface characteristics of one track only across the plug, and the other end 70 formed to continue the rail surface characteristics of both rails simultaneously and arranged for passage of the wheel flanges on either track.

3. In a track crossing structure a reversible revolvable track plug provided at one end with a formation adapted to match and continue the rail surface characteristics of one track only across the plug, and the other end 80 formed to continue the rail surface characteristics of both rails simultaneously and arranged for passage of the wheel flanges on either track and a vertically disposed circular housing at the intersecting points of the crossing tracks in which said plug is rotatably mounted.
85

4. In a track crossing structure a reversible revolvable track plug provided at one end with a formation adapted to match and continue the rail surface characteristics of one 90 track, a vertically disposed circular housing at the intersecting points of the crossing tracks in which said plug is rotatably mounted, and a loose disk at the lower end of said plug and upon which the plug rests.
95

5. In a track crossing structure a reversible revolvable track plug provided at one end with a formation adapted to match and continue the rail surface characteristics of one track, a vertically disposed circular housing 100 at the intersecting points of the crossing tracks in which said plug is rotatably mounted, an opening on the side of said housing, and an arm projecting from the side of the plug through said opening for rotating the 105 plug.

6. In a track crossing structure a reversible revolvable track plug provided at one end with a formation adapted to match and continue the rail surface characteristics of one 110 track, a vertically disposed circular housing at the intersecting points of the crossing tracks in which said plug is rotatably mounted, an opening on the side of said housing, and an arm projecting from the side of the 115 plug through said opening for rotating the plug, said arm arranged adjacent an overhanging shoulder of the housing to prevent lifting of the plug.

7. In a structure as specified in claim 5 120 said arm comprising an eyebolt screwed into the side of the plug.

8. In a structure as specified in claim 5 said arm being movable through an arc to rotate the plug, and a link pivotally connected to 125 the end of the arm for swinging the same back and forth.

9. A unitary structure of crossed railway rails, a vertically depending cylindrical housing at each rail intersection, a circular plug 130

- revolvably positioned in each housing and each plug formed on its upper end to continue the characteristic of a rail thereacross, an arm projecting from the side of each plug 5 beneath the tread of the rail, and linkage operatively connecting said arms, said linkage including a rock shaft extending between a pair of the rails, rockers on said shaft, and links pivoted to the rockers.
10. 10. A unitary structure of crossed railway rails, a vertically depending cylindrical housing at each rail intersection, a circular plug revolvably positioned in each housing and each plug formed on its upper end to continue the characteristic of a rail thereacross, an arm projecting from the side of each plug 15 beneath the tread of the rail, and linkage operatively connecting said arms, said linkage including a rock shaft extending between a pair of the rails, rockers on said shaft, and links pivoted to the rockers, and an operating rod 20 pivoted to one of said rockers.
11. A unitary structure of crossed railway rails, a vertically depending cylindrical
- housing at each rail intersection, a circular 25 plug revolvably positioned in each housing and each plug formed on its upper end to continue the characteristic of a rail thereacross, an arm projecting from the side of each plug beneath the tread of the rail, and linkage 30 operatively connecting said arms, said linkage including a rock shaft extending between a pair of the rails, rockers on said shaft, universal joints on said rockers, and links pivoted to the universal joints and 35 to said arms.
12. In a railway track crossing, a unitary structure of crossed rails, the rails running in one direction being of deeper section than those running in the opposite direction, a 40 layer of ties under the shallower sectioned rails, and a layer of ties extending transversely to the first mentioned layer under the rails of deeper section, both layers of ties being in firm contact and extending across their 45 respective tracks.

LUTHER SADLER.

CERTIFICATE OF CORRECTION.

Patent No. 1,713,008.

Granted May 14, 1929, to

LUTHER SADLER.

It is hereby certified that the above numbered patent was erroneously issued to the inventor "Luther Sadler, one-third to E. L. Fairbanks, and one-third to L. C. Treadway, both of Los Angeles, California", whereas said patent should have been issued to the inventor, said "Sadler and one-third to E. L. Fairbanks, of Los Angeles", said Fairbanks being assignee by mesne assignments of one-third interest in said invention, as shown by the records of assignments in this office; and that the said Letters Patent should be read with this correction therein that the same may conform to the record of the case in the Patent Office.

Signed and sealed this 30th day of July, A. D. 1929.

M. J. Moore,
Acting Commissioner of Patents.
